UNITED STATES PATENT OFFICE.

WILLIAM R. GARNER, OF ERIE, PENNSYLVANIA, ASSIGNOR OF ONE-FOURTH TO CHARLES JACOBSEN AND ONE-FOURTH TO A. F. JORSS, BOTH OF WASHINGTON, DISTRICT OF COLUMBIA.

COMBINED TELEGRAPH RELAY AND TELEPHONE.

Application filed January 20, 1920. Serial No. 352,770.

To all whom it may concern:

Be it known that I, WILLIAM R. GARNER, a citizen of the United States, and a resident of Erie, in the county of Erie and State of Pennsylvania, have invented certain new and useful Improvements in Combined Telegraph Relays and Telephones, of which the following is a specification.

My invention relates to improvements in the arts of telephony and telegraphy, and it consists in the constructions, combinations and arrangements herein described and claimed.

One of the foremost objects of my invention is to provide an instrument, hereinafter designated the relay, which has a telephone and telegraph key combined therein in such a manner that either may be employed in transmitting intelligence over a single metallic line, the earth being used as a return conductor.

A further object of the invention is to provide a telephone and telegraph key in combination to constitute a single instrument for the purpose named above.

A further object of the invention is to provide an instrument or relay wherein a telephone and telegraph key are combined, there being a sound-proof compartment in which the key operates, so that the sounds common to the operation of a telegraph instrument may not be heard to disturb others using the telephone or other similar instruments in the same room.

A further object of the invention is to provide an improved system of transmitting intelligence, comprising in combination a single metallic line and a combined telephone and telegraph instrument in connection with that line, so that the mode of communication common to each may be separately employed when desired.

Other objects and advantages will appear in the following specification, reference being had to the accompanying drawings, in which:

Figure 1 is a perspective view of the improved instrument or relay,

Figure 2 is a detail cross section on the line 2—2 of Figure 4, illustrating the sleeve on the switch in the upper sound-proof telegraph key compartment,

Figure 3 is a plan view of the instrument,

Figure 4 is a longitudinal section thereof,

but showing the receiver hook standard in elevation,

Figure 5 is a diagram illustrating the wiring connections employed and

Fig. 6 is a detail cross section taken on the line 6—6 of Fig. 4.

The general construction of the improved relay consists of a base 1 of suitable material, which is closed on all sides with the exception of the side 2, and has a sound-proof compartment 3 on top, in which compartment the telegraph key 4 works. The compartment is made sound-proof by means of the rubber or other cover 5, which is hinged at 6 for opening and closing and provided with a catch 7 at the front.

The key 4 is the same in construction as any ordinary telegraph key, its magnet 8 being located in the lower compartment, but the pole pieces of the magnet projecting through so as to act on the key, as clearly shown in Figures 2 and 4. When the proper connections are made, as described fully in the operation of the invention, telegraphic impulses entering over the line L in Figure 5, serve to attract the armature 9 of the key thereby causing the key to act as a sounder. A sounder as an independent instrument, is dispensed with in this improved relay.

Both the key 4 and switch 10 move in suitable slots 4^a and 10^a in the front wall of the cover 5, but in order to prevent the escape of sounds from the compartment 3, suitable sleeves 11, 12 are fitted around the key and switch respectively, so as to move with these members and keep the various slots closed at all times. The key 4 moves vertically while the switch 10 moves horizontally and in order that the cover 5 may be opened without carrying the switch 10 with it the slot 10^a has a bottom outlet 10^b which affords passage for the switch. The key 4 (see Fig. 5) has also proper contact making points, there being a wire 13 running from the pivot of the key to one of the magnet coils 8, and a wire 14 running from the contact 15 to the ground connection. The local battery B is connected in this wire.

A standard 16 has a telephone hook 17 on which the head-piece 18 is hung. This head-piece carries the receiver 19 and transmitter 20, the purpose of the arrangement

illustrated in Figure 1 being, to provide a combined receiver and transmitter which can be conveniently mounted on the head of the operator in using the instrument. As appears more fully below, it is necessary to raise the hook 17 when telegraphic impulses enter the instrument, a cam 21 with a finger-piece 22 being employed for this purpose should the head-piece be left on the hook for any reason, but ordinarily the head-piece is applied to the operator's head so that he can hear said impulses which are supposed not to otherwise escape from the compartment 3.

Multiple connector plates 23, 24, suitably insulated from each other and mounted in the open side 2 of the base 1, are employed for making the connection of various extension devices to the relay, as for example, the switchboard S, illustrated in Figure 5. The conductor 25 of the head-piece 18, is also connected to a pair of the screws of the plates 23, 24.

Ringing mechanism 26, including the bells 27, forms part of the telephone feature of the improved instrument. This ringing mechanism also includes the magnets 28 in Figure 5. Attention is now directed to the wiring in Figure 5.

Only a single metallic line L is employed. Various instruments of the various stations are grounded so that the earth forms the return conductor. As many branches similar to the branch 29 in Figure 5, are employed as there are stations along the line. A connection 30 from the branch 29 runs to the central movable contact 31 which is moved either into engagement with the contact 32 at the left or 33 at the right by the telephone hook 17.

When the hook 17 is lifted either by turning the cam 21 into the lifting position with the head-piece 18 still on the hook, or by removing the headpiece, at which time a spring which forms a part of the hook mechanism, lifts it, connection is made with wire 34 which runs to the binding screw 37 on the plate 24, opposite to the binding screw 38 to which the branch 29 is connected as clearly shown in Figure 5. A wire 35 runs from the contact 32 to one of the coils of the magnet 28, the other coil being grounded at 36.

Wires 39, 40 are embodied in the conductor 25, and are connected to the receiver 19 and transmitter 20, both of which are of an ordinary construction as clearly illustrated. Other wires 41, 42 run from the screws 37, 38 and are respectively connected to the wires 14, 13 which lead to the telegraph magnets 8.

60 The operation.

Assume the head-piece 18 to be hung on the telephone hook 17 and therefore the central movable contact 31 in engagement with the left contact 32. The operator at

some station along the line L (St for example), desiring to communicate with the station illustrated in Figure 5, presses a suitable ringing button, or better still, switch 43 in a wire 44 which connects the battery wire 14 with the line branch 29. This switch closes the ringing circuit, and is kept closed while talking continues from the sending station, whereupon current flows from battery b over the line L, branch 29, wire 30, contacts 31, 32, wire 35 to magnets 28, and from thence over wire 36 to ground, the current returning to the sending station St through the ground. The bells 27 are thus made to ring and the operator of the home station apprised of the telephone call.

Upon removing the head-piece 18 from the telephone hook 17, the bell ringing circuit is broken at the contacts 31, 32, since the contact 31 follows the pendent portion of the hook 17, which in turn rises into the position shown in Figure 5.

The talking circuit, being now completed, is as follows: From battery b to line L, over branch 29, wire 30, central movable contact 31, right contact 33, wire 34, screw 37, wire 39 to the instruments 19, 20 of the head-piece 18, returning via wire 40, screw 38 to ground G, thereafter returning to the sending station St via the ground plate C. It must also be observed that the wire 29 between the connection 30 and screw 38, has a switch Sw which is open when telephoning and closed only when the telegraph instrument is used either in receiving or sending telegraphic impulses. Under other conditions the switch is opened to the ground connecting position illustrated in full lines.

In sending telegraph impulses, the circuit is as follows: Upon depression of the key 4, current flows from the positive pole of the battery B, over wire 14 to contact 15, through the key to wire 13, over wire 42 to screw 38, over wire 29, through switch Sw which is then closed in the dotted line position, continuing over wire 29 to line L, reaching the remote station St where it passes over wire 29, switch Sw, wires 29 and 42 to magnets 8, thence to ground via wire 45 and returning to the negative pole of the battery B via the ground connections. A switch 46 in the ground wire 45 is closed at the receiving station St but should be open at the sending station to avoid locally shunting the sending impulses to ground. In both sending and receiving telegraph, the impulses of the sending key will be heard on all telephone receivers 19, including that of the sending operator, current being shunted thereto at the screw 38 at the transmitting station and the wire 30 at the receiving station.

In receiving telegraphic impulses, the circuit is as follows: From the remote station

over line L, branch 29, closed switch Sw, it being observed that when such impulses are received, the hook 17 is raised by means of the cam 21 in order to prevent the bells 27 from ringing or sounding at each impulse, continuing over wire 29 to screw 38 where the current divides, a part traveling over wire 40 to the head-piece instrument and the other part continuing over wire 42 to sounder magnet 8 and from thence returning to the remote station via the ground line 14. The divided portion of current flowing to the head-piece instrument 18, returns via wire 39, screw 37 and wire 41 to the ground connection 14. The operator may place the head-piece on his head and listen to the telegraphic sounds produced by the attraction of the armature 9, it being remembered that this portion of the mechanism is housed in the sound-proof compartment 3, from which no sounds can issue and hence cannot be heard unless the head-piece 18 is applied.

The advantages of the invention may be briefly considered. The use of but a single metallic line L effects a great saving in material. In view of the fact that in my invention both the telephone and telegraph instruments are combined in one, it becomes possible to use a single metallic line for the double purpose of alternately telegraphing and telephoning.

The use of a sounder as an independent instrument, is also entirely dispensed with, the telegraph key 4 being provided with the armature 9 which will serve the purpose of a sounder when used as above described. A feature of great convenience resides in the compactness of the instrument, which takes up but little room.

In the operation of the instrument in sending and receiving, a considerable amount of energy is saved by reason of the fact that the sounder is embodied in the key, thereby avoiding the customary synchronous movement of the sounder with the key in sending, this requiring a great deal of current. Also the relatively slight movement of the key-sounder avoids the present expenditure of energy now necessarily wasted in pulling the ordinary sounder through a distance four or five times greater than that traversed by the ordinary key.

While the construction and arrangement of the improved combined telephone and telegraph relay as herein described and claimed, is that of a generally preferred form, obviously modifications and changes can be made without departing from the spirit of the invention or the scope of the claims.

I claim:

1. An electrical instrument comprising an open base with a sound-proof compartment, a sub-station telephone set associated

with the base including ringing mechanism contained thereby; and telegraphing mechanism including magnets contained in the base with pole pieces projecting into said compartment, the telegraph key being operatively located in said compartment for cooperation with said pole pieces.

2. A telegraph instrument including a key, a sound-proof compartment housing a portion of the key and provided with an opening through which the key protrudes, and means preventing the escape of sounds from the compartment where the key protrudes, including a suitable sleeve carried by the key and covering the key opening.

3. The combination of a single metallic line, a substation telephone set with grounded ringing mechanism in normal readiness for a ringing impulse from the line, a grounded telegraph instrument combined with the ringing mechanism of the telephone set normally unaffected by a ringing impulse, but provided with switch means for conveying telegraphic impulses from the line to said instrument, and means for disconnecting said ringing mechanism at the time when said switch means is actuated.

4. The combination of a single metallic line, a substation telephone set, a connection by which said set is joined to the line, and a hook switch provided with contacts for keeping a grounded ringing mechanism normally in readiness for a ringing impulse from the line; a telegraph instrument including an electro-magnetically actuated key-armature, normally unaffected by a ringing impulse, but provided with switch means for joining said connection to said instrument for receiving telegraphic impulses; and means embodied in the telephone set preventing energization of the ringing mechanism by said impulses.

5. The combination of a single metallic line, a substation telephone set, a connection by which said set is joined to the line, and a hook switch provided with contacts for keeping a grounded ringing mechanism normally in readiness for a ringing impulse from the line; a telegraph instrument including an electro-magnetically actuated key-armature normally unaffected by a ringing impulse, but provided with switch means for joining said connection to said instrument for receiving telegraphic impulses, means embodied in the telephone set preventing energization of the ringing mechanism by said impulses, and a sound-proof compartment housing the telegraph instrument to prevent the escape of telegraphic sounds.

6. The combination of a single metallic line, a substation telephone set, a connection by which said set is joined to the line, and a hook switch provided with contacts for keeping a grounded ringing mechanism

- normally in readiness for a ringing impulse from the line; a telegraph instrument including an electro-magnetically actuated key-armature normally unaffected by a ringing impulse, but provided with switch means for joining said connection to said instrument for receiving telegraphic impulses, means embodied in the telephone set preventing energization of the ringing mechanism by said impulses, a sound-proof compartment housing the telegraph instrument to prevent the escape of telegraphic sounds, and a head-piece included in the telephone set so connected to the telegraph instrument that said telegraphic sounds may be heard by applying the head-piece.
7. The combination of a single metallic line, and a single station instrument in which a substation telephone set and telegraph instrument are combined, said set including a telephone hook switch closing a circuit from the line over a branch connection through a grounded ringing mechanism, a head-piece including a receiver and transmitter, being in electrical connection for operation when the hook switch is lifted,

the telegraph instrument comprising electro-magnets, with a switch for normal disconnection from said branch connection, closable to direct telegraphic impulses to said magnet when the head-piece is hung on the hook switch, and a telegraph key with an armature above said magnet constituting both the key of the sending means and the sounder.

8. An electrical instrument comprising a combined substation telephone set and telegraph, a hook switch and ringing mechanism associated with the telephone set, a branch line entering the instrument, two connections leading from said line, one to the receiving mechanism, the other to the telegraph, contacts included in said connections controlled by the movement of the hook switch to disconnect the telegraph when the telephone set is employed, and a cam for raising the hook switch of the telephone when the first switch is closed and the telegraph is employed, to prevent the telegraphic impulses energizing the ringing mechanism of the telephone set.

WILLIAM R. GARNER.
